CLAIM

The ornamental design for a connector plug for electronic game machine, as shown and described.

DESCRIPTION

FIG. 1 is a front, top and right perspective view of a connector plug for electronic game machine showing our new design;

FIG. 2 is a rear, bottom and left perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof; and,

FIG. 9 is a perspective view thereof, in use condition. The broken line showing of the environment is for illustrative purposes only and forms no part of the claimed design.
